(57) **CLAIM**

The ornamental design for an electric driver, as shown and described.

DESCRIPTION

FIG. 1 is a perspective view of a first embodiment of an electric driver.

FIG. 2 is a front elevational view of the first embodiment of the electric driver.

FIG. 3 is a rear elevational view of the first embodiment of the electric driver.

FIG. 4 is a right side view of the first embodiment of the electric driver;

FIG. 5 is a left side view of the first embodiment of the electric driver;

FIG. 6 is a top plan view of the first embodiment of the electric driver.

FIG. 7 is a perspective view of a second embodiment of an electric driver.

FIG. 8 is a front elevational view of the second embodiment of the electric driver.

FIG. 9 is a rear elevational view of the second embodiment of the electric driver.

FIG. 10 is a right side view of the second embodiment of the electric driver;

FIG. 11 is a left side view of the second embodiment of the electric driver; and,

FIG. 12 is a top plan view of the second embodiment of the electric driver.

The broken lines in the Figures are for environmental purposes only and form no part of the claimed design.
